UNITED STATES PATENT OFFICE.

LOUIS PFINGST, OF NEW YORK, N. Y., ASSIGNOR TO HIMSELF, AND W. P. WILLIAMS AND E. C. TRACY, BOTH OF CHICAGO, ILLINOIS.

CAR-AXLE BOX.

SPECIFICATION forming part of Letters Patent No. 354,219, dated December 14, 1886.

Application filed September 6, 1886. Serial No. 212,800. (No model.)

To all whom it may concern:

Be it known that I, LOUIS PFINGST, of the city, county, and State of New York, have invented a new and useful Improvement in 5 Axle-Boxes, of which the following is a specification.

This invention relates to the journal-box, bearing, and housing made use of in railway-cars. In this class of cars it is very important 10 that the parts have freedom of movement and great strength and lightness, because these cars are often heavily loaded and subject to lateral concussion in turning short curves and in sudden stopping and starting; and the object of my invention is to provide a box that 15 is oil-tight and dust-proof, and that combines freedom of movement with strength, lightness, and durability.

I make use of a combined sleeve and dust-collar around the journal—the sleeve to take the wear and the dust-collar to act with a dust-cap upon the box; and the journal-bearing is pivoted within the box, so as to accommodate itself to the inequalities in the position of the car upon the axle, and the box is made with lateral arms and base-pieces for the 25 springs, and vertical guide-rods are fastened to the sill of the car and connected with a braced bottom plate, and the springs surround 30 the guide-rods, and a cross-bearer and rubber buffers limit the downward movement when the car is heavily loaded. An oil-receptacle and wick provide a means of lubrication.

In the drawings, Figure 1 is a vertical section longitudinally of the journal. Fig. 2 is a vertical section transversely of the journal; and Fig. 3 is a plan view, partially in section.

The axle 1 is of ordinary character, and upon it is the sleeve 2, having around it, near 40 the back end, the dust-collar 3. This sleeve with its collar is removable from the axle when worn out, and another sleeve can be substituted, the same being pressed on by a suitable press or otherwise.

The journal-box 5 is of a suitable size and shape, and the bearing 4 is over the sleeve of the axle, and it is made hollow for the reception of oil, and there is a removable brass, 21, upon the under side of this box, to rest upon 45 the axle-sleeve.

At the sides of the bearing 4 are pivot-lugs

6, and upon these rest the U-shaped flanges 7, upon the inner faces of the box 5, so that the parts are free to swing upon the pivot-lugs and allow the brass 21 to set evenly upon the 55 sleeve when one side of the car is higher than the other. The brass 21 and base of the bearing 4 are slotted in line with the axle, and a wick is inserted in said slot to act as a medium for conveying the oil in the bearing 4 to the 60 axle-sleeve, to constantly lubricate the same.

Outside the box 5 there are the lateral arms 8, extending at front and back, and terminating as ring-shaped spring-bases 9, through which the vertical guide-bars 10 pass freely. 65 The arms 8 are considerably the widest at the box 5, and taper to the spring-bases, so as to be of the proper strength.

At the back of the box 5 is a septum, 23, and a circular projecting flange, 24, and within the latter is the dust-ring 25, that is drawn toward the dust-collar 3 by the bolts 26 and the helical springs 27, that are within recesses in the journal-box and act against the heads of the bolts 26. This dust-ring yields laterally within 75 the flange 24, and the faces of dust-ring and collar can slide on each other as the latter revolves against the former, so that dust is excluded.

The guide-rods 10 are secured at their upper 80 ends within the car-sill 12, and at their lower ends is the bottom plate, 13, with braces 14 at the ends extending up to the sill of the car, and the lateral braces 30, that extend inwardly beneath the car. The vertical guide-rods 11 85 are bolted at their lower ends to the plate 13 and pass at their upper ends into the sill 12, and these rods 11 are at the sides of the journal-box and guide the same, and at their upper ends are the socket-plates 19, on the under 90 side of the car-sill, and at 16 is a bearer above the journal-box 5, having a central rest upon such box, and ring-bearings at the ends for the rubber buffers 17, that surround the rods 11. These buffers limit the movement when the 95 car is heavily loaded and prevent concussion.

The spiral or helical springs 15 between the spring-bases 9 and the car-sill are of a sufficient strength to support the car and its ordinary load.

It will now be apparent that this improvement allows freedom of movement in the parts,

affords perfect lubrication to the bearing, and prevents dust passing into the box, and allowing the springs to act to advantage in supporting the car and yielding to the movement of the same. The check-plate 31 limits the lateral motion of the box on the axle, and the removable cap 20 covers the end of the journal-box.

I claim as my invention—

- 10 1. The combination, with the car-axle, of the sleeve and dust-collar on the same, the bearing 4, having pivot-lugs 6, the journal-box having internal U-shaped flanges for the pivots, and the septum, flange, dust-ring, bolts, and springs, substantially as set forth.
- 15 2. The combination, in a journal-box, with the septum 23 and circular projecting flange 24, of a sleeve, 2, and dust-collar 3, formed together and surrounding the axle, the dust-ring 25 within the flange 24, and the bolts and springs to hold the ring 25 against the flat face of the collar 3, substantially as specified.
- 20 3. The combination, with the journal-box having the lateral arms 8 and ring-shaped bases 9, of the guide-rods passing through the
- 25

same and the springs between the bases and the car-sill, the bearer 16, rubber buffers 17, and guide-rods 11, substantially as set forth.

4. The combination, with the car-axle, wheels, and axle-boxes, of removable sleeves 30 upon the journals of the axle, each sleeve having upon and integral with it a dust-excluding ring, substantially as specified.

5. The combination, with the car-axle, of a bearing, 4, having pivot-lugs 6, and the journal-box having internal U-shaped flanges for the pivots, substantially as specified.

6. The combination, with the axle 1, its sleeve 2, box 5, and flanges 7, of the hollow bearing 4, lugs 6, and the brass 21, said brass 40 21 and the base of the bearing being slotted and having a wick therein, substantially as specified.

Signed by me this 3d day of September, A. D. 1886.

LOUIS PFINGST.
